UNITED STATES PATENT OFFICE

ORRIN COLLIN VAN NESS, OF POMME DE TERRE, MINNESOTA.

GRAIN-FEEDER AND BAND-CUTTER FOR THRASHING-MACHINES.

SPECIFICATION forming part of Letters Patent No. 291,480, dated January 1, 1884.

Application filed September 29, 1883. (No model.)

To all whom it may concern:

Be it known that I, ORRIN C. VAN NESS, a citizen of the United States, residing at Pomme de Terre, in the county of Grant and State of Minnesota, have invented new and useful Improvements in Grain-Feeders and Band-Cutters for Thrashing-Machines, of which the following is a specification.

My invention relates to grain-feeders and band-cutters for thrashing-machines, and has for its purpose to provide simple and efficient mechanism for feeding the bundles to the thrashing-cylinder and cutting the bands, said apparatus being so constructed that it can be adjusted to the required height and angle when in use, and be folded upon and transported with the machine.

My invention consists in the novel construction and combination of parts hereinafter described, and pointed out in the claims.

Referring to the accompanying drawings, Figure 1 is a longitudinal vertical section taken through the apparatus and a portion of the thrasher. Fig. 2 is a side elevation, showing the parts folded and in position for transportation with the machine.

A in said drawings designates the thrashing-machine, which is of the usual form and construction, and A' is the thrashing-cylinder. At the end of the machine, and just opposite the feed-opening leading to the cylinder, is journaled a roll, B, having its bearings in the forked ends of bars B', which are fastened to each side of the frame of the thrasher, its journals being retained within the forks b of said bars by means of pins b', which pass through the extremities in front of the journals. Side boards, C, are supported at one end by the shaft of the roll B, and at the opposite ends are hinged to similar but longer pieces, C', by means of hinges c, attached to their upper edges in such manner that, when extended, their ends will abut against each other, as shown in Fig. 1, forming an extension-frame, of which the longer portion, C', will not be far from horizontal, while the shorter portion next the machine is inclined downward.

At or near the extreme end of the side pieces C' is journaled a roll, D, and at or near the point where the long side boards meet the shorter ones is journaled a roll, D', the bearings therefor being formed in the side pieces.

Over the rolls B and D, and having support upon the intermediate roll, D', I pass an apron or carrier, E, having a width equal to the length of the thrashing-cylinder. This apron may be made of canvas or other flexible material, or it may be composed of sprocket-chains having parallel transverse slats. When canvas or similar material is used, transverse slats e are arranged thereon at intervals, and upon each slat are placed at intervals feeding-spikes e', which project upward, and are at the same time inclined toward the outer end of the frame. Motion is imparted to the roll or rolls supporting the apron by any suitable means—such as a belt from a pulley on the machine—and it is fed forward at the proper rate of speed to supply the grain-bundles to the thrasher.

F designates the band-cutter carrier, which is composed of a belt of canvas, f, running over two rolls, G G', of which the latter is journaled but a short distance above the delivery end of the apron, the roll G being arranged at such a point that the belt f and the grain-carrier converge toward each other.

Upon the belt f are mounted transverse strips f', carrying cutters f'', which sever the band as the bundle passes between the belt and apron, and also serve to spread the straw and feed it evenly to the thrashing-cylinder. The belt f is driven at a considerably greater speed than the feed-apron, and as the spikes e hold the lower side of the bundle it is evident that after cutting the band the projecting knives will force or advance the upper part of the straw in each bundle into the machine, thus securing a gradual and uniform feed to the thrashing-cylinder.

Beneath the delivery end of the apron E, I place an inclined board or chute, I, which receives the grain falling from the straw and carries it to the separator.

Upon the outer end of the extension-frame C' are pivoted legs L, which support it when in operation.

By hinging the carrier in the manner shown and described it can be set in or adjusted to any position required by the nature of the work. Moreover, when the machine is not in operation the grain-carrier and the band-cutter carrier may be swung or folded up to a vertical position at the feed end of the machine,

where they are held by hooks M or other devices.

Having thus described my invention, what I claim is—

- 5 1. The combination, with a thrashing-machine, of a roll, B, journaled at the feed end of the machine, side pieces C, pivoted at one end adjacent to the roll, side pieces C', hinged to the other ends of the pivoted side pieces, to a roll, D, journaled at the outer ends of the hinged side pieces, a traveling grain-carrier mounted on the rolls, a traveling band-cutter carrier arranged above the delivery end of the carrier, and a cutter secured to said cutter-carrier, substantially as described.
- 10 2. The combination, with a thrashing-machine, of a folding grain-carrier frame pivoted adjacent to the feed-opening of the machine, a band-cutter carrier pivoted above and adjacent to the said feed-opening, the grain-carrier and cutter-carrier being capable of folding up against the feed end of the machine, and means for holding the carriers in such position for transportation, substantially as described.
- 15 3. The combination, with a thrashing-ma-

chine, of an endless traveling grain-carrier and an endless traveling band-cutter carrier converging toward each other, and both pivoted at the feed end of the machine to fold up for transportation, and means for holding the carriers in such position, substantially as described.

4. The combination, with the thrashing-machine, of the carrier having a jointed extension-frame, and the bars supporting said frame having forked ends to receive the journals of the roll carrying the apron, substantially as described.

5. The combination, with the grain-carrier having inclined spikes, of the band-cutter and straw-spreader, said carrier and band-cutter converging toward each other, and the band-cutter traveling at a greater speed than the grain-carrier, substantially as described.

In testimony whereof I have hereunto set my hand in the presence of two subscribing witnesses.

ORRIN COLLIN VAN NESS.
